VACUUM TUBE

Application filed May 2, 1928. Serial No. 274,399.

This invention relates to vacuum tubes and particularly to vacuum tubes adapted to be energized by alternating current. The invention is an improvement over the application of Walter Louis Krahl entitled "Vacuum tube construction and circuit therefor," Serial No. 156,947, filed December 24th 1926.

In operating a thermionic tube with alternating current some difficulty has been experienced in eliminating the hum due to the alternating cycle. There are several reasons why a hum may be produced in the output side of the tube and great care is necessary in designing a tube and circuit therefor to lower the hum to a minimum so as not to be objectionable in the radio receiving set. Any change in the potential of the grid of the tube is naturally amplified in the plate circuit and hence it is necessary to maintain the grid circuit of the tube as free as possible from changes in potential arising from sources outside of the input circuit. In an alternating current thermionic tube it sometimes becomes desirable to have a portion of the grid circuit common with a portion of the heater circuit, and this is particularly true in tubes which have a common connection for the cathode and the heater of the tube permitting the use of a four terminal base or where the cathode is itself the heater for the tube. In both of these cases there is a drop in potential along the common cathode and heater lead due to the resistance thereof and, therefore along a portion of the grid circuit. This drop in potential causes a variation of potential on the grid due to the alternating current and the result is a variation in the plate circuit which gives rise to an objectionable hum. Inasmuch as the drop in potential along the common lead is proportional to the current flowing therein it is necessary to maintain the current as low as possible so that the design of the tube is limited to the use of a low current.

It is one of the objects of the present invention to eliminate this common cathode and heater circuit connection within the tube and still permit the use of four terminals on the base of the tube and the use of higher currents if desired.

Other objects of the invention will be apparent as the description thereof proceeds.

The invention has been illustrated in the accompanying drawing which shows a perspective view of a vacuum tube embodying the invention with portions of the tube broken away to more accurately show the same.

For purposes of illustration I have shown a heater type tube 10, somewhat similar to that shown in the above entitled application in which a tubular cathode 11, is adapted to be heated by a single straight filament 12 passing therethrough, both of these elements being supported from a press 13, which is formed integral with the usual transparent envelope 14 supported upon a base 15 which carries the terminals for making the necessary connections to the tube. The filament 12 is supported at its lower end upon a conductor 17 which is sealed in the press 13 and which is connected by a wire 18 to one of the heater terminals 16 mounted on the base 15. The upper end of the filament 12 may be supported by a spring wire 19 which is in turn attached to an upright conductor 20 extending parallel to the cathode to a point below the same where it is bent inwardly and downwardly to be sealed in the press 13. A glass bead 21 is sealed upon the upright conductor 20 and has sealed into it two supports 22 and 23 for rigidly supporting respectively the upper end of the plate 24 which surrounds the cathode 11 and the upper end of the grid 25 which is interposed between the cathode and the plate. The lower end of both the plate and grid are supported respectively by means of one or more conductors 26 and 27 sealed in the press. One of these conductors 26 from the plate is connected by means of a wire 28 to the plate terminal 29 at the base of the tube, while one of the supports 27 for the lower end of the grid is connected by means of a wire 30 to the grid terminal 31 on the base. The lower end of the cathode 11 may be rigidly attached to a conductor 32 which is sealed in the press 13 and connected by means of a separate wire 33 to the other filament terminal 34. The upper end of the cathode 11 may be rigidly supported by

means of a strip 35 upon an auxiliary upright 36 which is sealed in the glass bead 31 and therefore insulated from the other elements. The conductor 30 which is electrical-
5 ly connected to the upper end of the filament 12 is connected by means of the wire 37 to the filament terminal 34.

The filament terminals 16 and 34 may be connected to the secondary 38 of a trans-
10 former 39 the primary 40 of which may be connected across a source of alternating cur-
rent 4 as shown.

It will be noted that the cathode extends
15 beyond the plate and grid at both ends so as to form an effective shield between them and the filament to eliminate hum which might otherwise arise from the direct emission of the filament to the grid and plate.

It will be evident from the above descrip-
20 tion that the upper and lower ends of the filament 12 are connected respectively to terminals 34 and 16 on the base 15 and that the connection to the cathode 11 is made by the wire 33 entirely separately from the filament circuit, down to the filament terminal 34 at the base of the tube. Inasmuch as the terminals on the base of the tube are made of a conducting material having low resistance, there is practically no potential drop in the
25 terminal itself due to the alternating current passing through the terminal, and if the grid return lead 42 of the circuit is connected directly to the corresponding terminal on the socket into which the tube fits, the drop in
30 potential in this circuit will be so small as to be absolutely negligible so that substantially no effect is produced on the grid of the tube.

It will be seen, therefore, that I have pro-
35 vided a means to absolutely eliminate hum arising through an alternating potential drop in the grid circuit of a tube provided with four terminals to fit into a standard four terminal socket and which is not dependent on the current used to energize the heater.

40 While I have shown the invention in connection with a heater type tube of a certain specific construction, it is apparent that the invention is applicable to any heater type tube. I do not, therefore, desire to limit myself to the specific construction described but to interpret the invention broadly within the scope of the appended claim.

45 What I claim is:

50 In a vacuum tube, an envelope, a cylindri-
cal cathode within said envelope, a single straight filament within said cylindrical cath-
ode, anode and control electrode elements within said envelope, a base on said envelope,
55 a terminal on said base, a connection between said terminal and one end of said filament, a second terminal on said base, a connection between said second terminal and the other end of said filament, and a separate connec-
60 tion between said cathode and one of said ter-
65 minals, said cathode extending beyond both extremities of said anode and control electrode.

In testimony whereof, I affix my signature.

ROBERT HARDING, JR.
